(57) **CLAIM**

We claim the ornamental design for a door for a countertop oven, as shown and described.

DESCRIPTION

FIG. 1 is an isometric view, from the top front right, of the door for a countertop oven.

FIG. 2 is an elevation view of the front of the door for a countertop oven.

FIG. 3 is an elevation view of the right side of the door for a countertop oven.

FIG. 4 is an elevation view of the left side of the door for a countertop oven.

FIG. 5 is a plan view of the top of the door for a countertop oven.

FIG. 6 is a plan view of the bottom of the door for a countertop oven.

FIG. 7 is an isometric view, from the top front left, of the interior of the door for the countertop oven in an open position.

FIG. 8 is a plan view, from the top, of the interior of the door for the countertop oven in an open position; and,

FIG. 9 is an isometric view, from the bottom back right, of the rear of the rear of the countertop oven in an open position.

The broken lines represent the environment in which the article resides and forms no part of the claimed design.

1 Claim, 6 Drawing Sheets
